UNITED STATES PATENT OFFICE

118,760

DESIGN FOR A TEXTILE FABRIC OR SIMILAR ARTICLE

Ruth Schmidt, Jamaica, N. Y.

Application December 13, 1939, Serial No. 88,850

Term of patent 3½ years

To all whom it may concern:

Be it known that I, Ruth Schmidt, a citizen of the United States, residing in Jamaica, city of New York, county of Queens, and State of New York, have invented a new, original, and ornamental Design for a Textile Fabric or Similar Article, of which the following is a specification, reference being had to the accompanying drawing, forming a part thereof.

The figure of the drawing is a plan view of a textile fabric or similar article showing my new design.

The design consists of an arrangement of stripes, as shown in the drawing, extending longitudinally of the fabric. The design unit extends from the stripe along one edge of the figure to the interior edge of the stripe on the opposite edge of the figure. This design unit is repeated laterally of the fabric.

I claim:

The ornamental design for a textile fabric or similar article, as shown and described.

RUTH SCHMIDT.
